UNITED STATES PATENT OFFICE.

FINIS E. LACK AND ERNEST LACKEY, OF PADUCAH, KENTUCKY.

DESIGN FOR A HARNESS-RACK.

42,635.

Specification for Design.

Patented June 18, 1912.

Application filed January 23, 1912. Serial No. 672,971. Term of patent 7 years.

To all whom it may concern:

Be it known that we, FINIS E. LACK and ERNEST LACKEY, citizens of the United States, residing at Paducah, in the county of McCracken and State of Kentucky, have invented a new, original, and ornamental Design for a Harness-Rack, of which the following is a specification.

Reference is had to the accompanying drawing, in which the figure is a perspective view of a harness rack, showing our ornamental design.

As shown in the drawing the design consists of an upright bar or back 1, a vertical series of horizontal arms 2, a straight inclined arm 3, and a vertical terminal hook 4. The horizontal arms 2, which are of equal length, extend forwardly at intervals from the upright bar or back 1, which has a short straight vertical portion extending above the top horizontal arm of the series. The inclined arm, which extends forwardly and upwardly from the upper end of the short vertical upper portion of the bar or back 1, overhangs the said top horizontal arm of the series.

The horizontal arms 2, which are arranged in parallelism, are provided at their outer ends with upwardly projecting bulb-

ous heads 5, and they have longitudinal ribs 6 extending along the median line of their lower faces and merging into upright ribs 7 of the bar or back 1. The inclined arm 3 is also provided at its lower face with a longitudinal rib 8, which merges into the rib 7 of the straight upper portion of the said bar or back 1.

The vertical hook 4, which is curved, is arranged transversely of the harness rack in a plane at right angles to the plane of the said arms and consists of a shank portion 9, extending upwardly from the upper end of the inclined arm 3 and a curved bill 10 extending laterally from the top of the shank and then downwardly. The hook 4 has a flat inner face and a rounded outer face.

What we claim is:—

The ornamental design for a harness rack, as shown and described.

In testimony that we claim the foregoing as our own, we have hereto affixed our signatures in the presence of two witnesses.

FINIS E. LACK.
ERNEST LACKEY.
